Primary Examiner — Ricky Pham(74) *Attorney, Agent, or Firm* — Renner, Otto, Boisselle & Sklar, LLP(57) **CLAIM**

The ornamental design for a chair, as shown and described.

DESCRIPTION

FIG. 1 is a perspective view of a chair showing my new design.

FIG. 2 is a front view thereof.

FIG. 3 is a rear view thereof.

FIG. 4 is a left side view thereof, a right side view being a mirror image thereof; and,

FIG. 5 is a top view thereof.

Any unshown surfaces do not contain any ornamental features that contribute to the claimed design.
